Frederick A. Daniels, Tarrytown, N. Y., assignor to Eagle
Pencil Company, a corporation of Delaware

Application January 12, 1954, Serial No. 28,481

Term of patent 14 years

(Cl. D74—24)

To all whom it may concern:

Be it known that I, Frederick A. Daniels, a citizen of the United States, residing at Tarrytown, county of Westchester, and State of New York, have invented a new, original, and ornamental Design for a Mechanical Clutch Lead Pencil, of which the following is a specification, reference being had to the accompanying drawing, forming part thereof, and in which

Fig. 1 is a perspective view of a mechanical clutch lead pencil, showing my new design;

Fig. 2 is an elevational view thereof, and

Fig. 3 is a transverse sectional view taken on line 3-3 of Fig. 2.

The essential features of my design reside in the portions shown in solid lines on the drawing.

I claim:

The ornamental design for a mechanical clutch lead pencil, substantially as shown and described.
